UNITED STATES PATENT OFFICE

2,050,257

CONCRETE FORM

Albert F. Bemis, Newton, Mass., assignor to Bemis Industries, Incorporated, Boston, Mass., a corporation of Delaware

Application July 18, 1934, Serial No. 735,809

10 Claims. (Cl. 25—131)

This invention relates to an improved method of forming walls of cementitious material and to walls which are produced as a result of the method as well as to form elements employed for this purpose.

5 In some respects the present invention comprises a further development of and improvement upon the method and construction disclosed in my copending application Serial No. 667,846, filed April 25, 1933.

10 Heretofore it has been customary in the erection of walls of cementitious materials such as concrete walls to assemble forms including numerous frame elements and concrete-retaining plates or temporary boarding, and to pour cement into the form thus erected. The erection of the temporary forms and the stripping of the same from the cement has been a troublesome and relatively expensive operation.

15 The present invention affords a method of concrete construction which involves the erection of forms without necessity of fitting individual form boards in place. The form proper may comprise sheet material which is relatively flexible, such as a rather heavy fabric, e. g. burlap. Fabric of this character is relatively inexpensive, it may be readily shipped and handled and it need not be stripped from the set concrete.

20 In accordance with this invention, the form may be provided with a simple framework to support the sheet material in suspended position. In general, the framework may include opposite sill strips, corresponding girt strips and connecting uprights therebetween. Uprights may be located at corners and wall intersections and, in the case of a long straight wall, at intervals between corners or intersections, to support longitudinal frame elements or girt strips from which the sheet material is suspended. The framework 25 may be constructed out of readily available wooden elements such as two by four inch strips, or it may include standardized parts, some of which may be adjustable in length.

25 Preferably the sheet material may be substantially preformed to define a plurality of cellular sections; thus, the form proper is characterized by opposite face sheet portions of somewhat flexible or readily deformable material which are interconnected at intervals by ties which preferably may be of the same fabric as the form itself. Thus when burlap is employed in the form proper, numerous burlap webs interconnect the opposite face sheet portions of the form, these webs being relatively porous so that the concrete 30 can penetrate the interstices of the fabric to

permit the integral joining of the concrete with-in adjoining cells.

In order to aid the proper disposition of the fabric in the form proper, the supporting framework preferably is arranged to receive certain 5 retaining and reinforcing elements which may conveniently be metal bars. Preferably the adjoining sections of the form proper are arranged to afford loop portions at the ends of each web, the rods being inserted in these loop portions 10 when the fabric form is being constructed.

Further features of the invention relate to the structural arrangement and characteristics of the framework and its component parts which permit facile erection and disassembly of the 15 framing.

In the accompanying drawings:

Fig. 1 is a vertical sectional view of a form erected in accordance with this invention;

Fig. 2 is a sectional view of a typical portion 20 of a fabric form proper;

Fig. 3 is a sectional view of a fabric form section which is employed at a corner or wall intersection;

Fig. 4 is an isometric view of a corner portion of 25 the lower framework which may be employed with this type of construction;

Fig. 5 is a plan view of a part of the lower framework or sill portion of such a form;

Fig. 6 is an isometric view of a typical corner of 30 the upper portion of the framework of the form;

Fig. 7 is a top plan view of a corner portion of the form;

Fig. 8 is a top view showing the arrangement 35 of the frame at a wall intersection;

Fig. 9 is a broken plan view of a part of the upper portion of the form as it may be arranged when a relatively long straight wall is being provided;

Fig. 10 is a horizontal section of a part of a 40 completed wall constructed in accordance with this invention;

Fig. 11 is a broken top plan view of the corner portion of an optional frame arrangement;

Fig. 12 is a broken vertical section of a form in 45 which a frame of the type illustrated in Fig. 11 is employed;

Fig. 13 is an elevational detail of an arrangement which may be employed with the embodiment of the invention illustrated in Figs. 11 and 50 12;

Fig. 14 is an isometric view of a corner portion of a temporary sill assembly which may be employed in framework of the type disclosed herein; and—

Fig. 15 is a diagrammatic detail showing the arrangement of the fabric sections in a typical wall.

While this invention may be employed in different environments and for different purposes, it is particularly adapted to the erection of foundation walls. For this purpose a footing 1 may first be formed of concrete in the conventional manner. A lower frame may then be arranged on the footing. This frame may include opposite wooden strips or temporary sills 2, which may be cut from ordinary two inch by four inch stock. These strips tend to remain in place due to their own weight and the weight of the superposed framework but they may also be connected by nailing to stakes 3 which are driven into the ground at intervals adjoining the footing 1 in the manner illustrated in Fig. 1. At the corners, the ends of the strips 2 may be brought into abutting engagement, as illustrated in Fig. 4, and splicing pieces 5 may then be nailed to the adjoining ends of the two strips to hold them in place.

At corners, wall intersections, and at intervals therebetween, if desired, assemblies of uprights may be connected to the temporary sills 2. Thus at a corner four uprights 6 may be secured as by nails 7 to the temporary sills 2, these uprights having a height substantially of the order of the height of the wall which is to be poured. When the uprights 6 have been arranged at one corner of the form in this manner, a unit of the upper framework or temporary girt structure may be connected to the uprights. Corner units 10, such as shown in Fig. 6, may be preformed and comprise pairs of parallel strips 11 connected to each other by spacer members 13.

After one of the corner units 10 is thus disposed on the corresponding assembly of uprights 6 it may be braced in approximate position by diagonal braces 19; the longitudinal framing for the upper part of the form may then be connected to one part of the corner unit. As shown in Figs. 6, 7 and 9, such framing may conveniently be in the form of a preformed unit 14 comprising parallel side rails 15 which are connected near their ends by wooden pieces 16, the spacing of the members 11 of the corner units and of the parallel rails 15 of the longitudinal units being the same. A unit 14 may be connected to the already erected unit 10 by means of wooden splicing strips 12 secured by bolts 13^a to the ends of the adjoining units, as shown in Fig. 6. The end of the unit 14 which is remote from the first corner may then be connected to a second corner unit such as the unit 10^a (Fig. 8) which is supported on uprights 6 arranged in the manner already described.

By following this general method of procedure, a light, skeletonized framework may be erected to define the entire wall structure, it being obvious that, where a relatively long straight wall, uninterrupted by corners, is desired, uprights 6 may be disposed beneath the adjoining ends of straight units 14, as indicated by dotted lines in Fig. 9. The rails 15 of the units may then be connected by strips 12 in the general manner already described.

After the framework has been initially erected, the uprights may be brought accurately into vertical position by moving the diagonal braces 19 where necessary. If desired, accurate leveling of the upper frame may be obtained by placing wooden shims or wedges between the lower portions of the temporary sills 2. However, especial care in leveling the framework is not essential,

since the upper surface of the poured concrete will be below the top of the framework.

After the temporary framework has been erected in the general manner described, the form proper may be connected thereto. The form proper may consist essentially of two kinds of units formed of sheet material. In the major portion of the wall structure, i. e., beneath the longitudinal units 14, a series of cellular elements, formed, for example, of burlap, may be used. These cellular elements each are formed of a single piece of burlap arranged as shown in Fig. 2 to provide a substantially U-shaped element having a web portion 21 with loops 22 defined at each of its ends, stitching 23 being provided for this purpose. From the loops 22 the burlap may extend in face sheet portions 24 which in practice are joined to the looped portions of the adjoining section. Thus the ends of the portions 24 of one cellular section are brought about the loops 22 of the adjoining section and the web portion 21 of the second section closes the fourth side of the first section. A series of units or sections may thus be joined together to provide face sheet portions having a size substantially conforming to that of the wall to be erected. At the end of a row of joined sections of this type, the last section will be provided with face portions 24 having free margins which may be connected to an adjoining section in situ. At the assemblies of uprights, as at corners and wall intersections, special form sections 26 may be provided, such as shown in Fig. 3, wherein the sheet material is sewed up into the form of a hollow square having loop portions 22^a at each of its corners. I have found it preferable to have the warp strands of the fabric extend vertically of the units and weft strands transversely thereof.

When an assembly of sections, such as shown in Fig. 2, are joined to a corner section, the free edges of the face sheet portions 24 of the last section may be fastened about the loop portions 22^a of the corner unit by sewing or by wire staples 85 (Fig. 15). At the opposite end of a row of fabric sections face sheet portions 24^a may be stitched to provide free edges similarly to be secured to a square or corner section 26 as diagrammatically indicated at the right of Fig. 15.

In practice rods 30, for example of cold rolled steel, may be inserted in the loops 22 and 22^a, the loops having a light frictional engagement with the rods permitting the latter to be readily fed or worked through the loops when necessary. An assembly of burlap sections to define a straight wall portion may be assembled with its rods in a suitable manufacturing establishment so that the rods and burlap sections may be rolled up into a bundle and brought onto the building site. Corner sections 26 may be similarly preformed and shipped.

The rails 11 and 15 of the upper framework may have screw eyes 32 mounted therein at distances corresponding to the spacing of the loops 22 of the burlap sections, while the sill strips 2 may similarly be provided with screw eyes 33. When the parts of the framework are brought into proper vertical positioning in the manner described above, the screw eyes 32 and 33 are in proper vertical alignment. Each rod 30 may first have its upper end inserted in the proper screw eye 32 and thereafter its lower end may be inserted in the corresponding screw eye 33. In practice the rods at one end of an assembly of burlap sections may be bent sufficiently and/or the burlap worked along the rods to a sufficient

extent to permit the proper location of the first rods of the row in this manner, whereupon successive rods of the burlap assembly may be similarly arranged in corresponding screw eyes. Obviously the rods 30 at the corners of each unit 26 are similarly mounted with their ends in screw eyes 32 and 33. The face sheet portions 24 and 24^a of the wall units may be connected to the corner units 26 by stitching or wire staples 85. The upper portion of the burlap form proper may then be tied by ductile wire 35 to each of the screw eyes, as illustrated in Fig. 1. Thus the burlap form is positioned in the frame so that the upper margin of the face sheet portions of the form proper are disposed above the lower parts of the longitudinal rails 15, while the lower margins of the burlap sections are disposed below the upper surfaces of the temporary sills 2. A fabric form consisting of a series of cellular units is thus suspended from the framework to define the entire wall structure.

The concrete may then be poured into the cellular units provided by the burlap. Preferably the pouring is effected at intervals along the wall assembly, thus to afford a more uniform effect and to avoid distention of the burlap at one end of the wall while the burlap cells in the opposite ends are empty. Thus in practice the cells or burlap sections 26 at the corners and wall intersections may first be poured; then alternate sections therebetween may be poured; and if there should be any odd section in a straight wall section, this may then be poured. Lastly the remaining sections may be poured. In order to aid firm interlocking of the face sheets with the wet concrete and to avoid possible surface irregularities in the concrete, the face sheets preferably are pressed against the concrete by troweling during or immediately after pouring. After concrete has been poured to substantially one half the height of each section the cement may be tamped if desired, and it may again be tamped when the unit has been substantially filled. Preferably the level of the poured concrete may be substantially even with the upper ends of uprights 6.

The concrete employed may be of a conventional type, being, for example, sanded rather richly and may include small stone rather than coarse gravel. What is known commercially as "vibrated" concrete has been found relatively satisfactory for this purpose.

After the concrete has initially set, for example, within twenty-four hours, the rods 30 may be slid out of the loops by being pulled out of the top of the form assembly. Thereafter the temporary framework may be disassembled and removed from the poured cementitious material and the burlap form proper. The resulting wall may be characterized by slightly bulged burlap face sheet portions between the loops at the ends of the web sections 24. If desired, the loops may be slit with a knife either before or after the removal of the rods. In order to aid in waterproofing such a wall, the burlap face sheet portions may be coated with a suitable water-resistant or repellent material such as asphaltic composition. If a flush wall surface is desired, a continuous coating of stucco may be disposed over the burlap face sheet portions, as designated by numeral 40 in Fig. 10.

Figs. 11, 12 and 13 illustrate an optional embodiment of this invention in which the lower portion of the framework for the form may be of any suitable type such as that already disclosed.

The upper portion of the form may comprise two kinds of units, namely, preformed hollow squares 56, which are located at wall intersections and at intervals therebetween, and longitudinal rails 51, which are adapted to be secured in adjustable overlapping engagement with each other and also to be secured at intervals to the square units 56. At intervals along a straight-wall section, as shown for example in the left-hand portion of Fig. 11, a unit 56 may be disposed between inner and outer rails 57 to act as a spacer, while a unit 56 is obviously connected to the ends of rails 57 at corners or wall intersections, as shown at the right of Fig. 11.

Each unit 56 may conveniently comprise four 15 wooden pieces defining a hollow square and secured to each other by any suitable fastening means, openings being provided at the corners of the square to receive clamping bolts 60 or any suitable fastening means, such fastening means 20 also being adapted to pass through openings in the rails 57. The rails themselves may be provided with spaced openings to receive fastening means such as bolts 64 to permit the rails to be arranged in adjustable overlapping position so 25 that two or more rails may be secured to each other to form a straight rail assembly of any desired length. Thus a girt assembly is provided which is readily adjustable to different sizes and requires but two types of parts in its construction, namely, the square units 56 and the rails 57.

In this embodiment of the invention the rails may be provided with notches 63 and corresponding notches 64 may be afforded at the corners of the square sections 56 to receive the rods 30. Any 35 suitable fastening means such as conventional wire hasps 65 (Fig. 13) may be associated with these notches to hold the rods 30 in place.

Fig. 14 illustrates an optional arrangement which may be employed at the corners of assemblies of temporary sills. At the exterior corners preformed angular pieces 51 may be employed, being spliced to straight rail sections or strips 2^a by means of splicing plates 53. At an interior corner a diagonal brace 52 may be provided to 45 connect the ends of rails 2^a. This arrangement is particularly advantageous when the rails 2^a are provided in a range of standardized or modular lengths to permit the erection of walls having 50 dimensions conforming to a definite modular system. It is evident that in general the principles of this invention may be employed with especial facility when walls having modular dimensions are being erected.

It is evident that this invention permits the 55 convenient erection of concrete forms without requiring highly skilled labor and without the construction of elaborate wooden forms. The framework required by this type of construction may be relatively simple and easily erected and 60 may be conveniently formed of readily available material such as two by four inch stock or of such parts in conjunction with standardized elements such as the squares 56 and rails 57. The parts may be cut to size and provided with openings for connecting bolts, the screw eyes, hasps, etc. before they are brought to the site where the wall is to be erected.

In most cases the burlap units may be preformed except for the connections of free edges 70 of units at corners in the manner described supra. This arrangement permits the employment of relatively flexible sheet material such as burlap as the major pressure sustaining factor in the wall. The arrangement of the rods 30 aids the 75

proper maintenance of the burlap in position as the wall is poured, and the wire ties 38 effectively oppose the tendency of the poured concrete to pull the burlap downwardly away from the upper 5 part of the framework.

While for convenience of illustration, particularly in Figs. 2, 3 and 15, the burlap is shown drawn tightly between the rods at the corners of the cells or cellular units, in practice the burlap 10 may, if desired, be arranged somewhat loosely between these elements. Accordingly, the bulging of the sheet sections under the pressure of the poured cement not only may result from some 15 slight stretching of the fabric, but also may be due to the dimensions of the burlap sections between adjoining rods.

In practice the weight of the concrete and its 20 interlocking engagement with the meshes of the burlap may cause a slight sagging of the mid portions of rail sections 15 or 57 between the assemblies of uprights. Accordingly the concrete is 25 poured somewhat below the upper edge of the burlap, obviously being capable of setting to afford a level surface upon which the sills of the 30 house may be secured by grouting or the like, as desired.

Since the rods and wooden framework are removed from the form, they may be used repeatedly, the burlap remaining with the form affording 35 an inexpensive means which affords an excellent ground for the application of waterproofing materials, stucco or the like.

It should be understood that the present disclosure is for the purpose of illustration only and 35 that this invention includes all modifications and equivalents which fall within the scope of the appended claims.

I claim:

1. A form arrangement comprising a horizontal, generally rectangular upper frame, supports 40 for said frame, a form including opposite face sheets suspended and depending from the frame to define opposite faces of a wall to be poured, tension elements extending between said sheets, 45 and spaced rows of substantially vertical rods secured to said frame and to the sheets to afford reinforcing means for the latter.

2. A form arrangement comprising a horizontal, generally rectangular frame, supports for said 50 frame, a form including opposite face sheets suspended from the frame to define opposite faces of a wall to be poured, tension elements extending between said sheets, a plurality of rods extending downwardly from the frame, the sheets being provided with looped portions receiving the rods 55 extending therethrough, and a footing to which the lower ends of the rods are connected.

3. A form arrangement comprising a footing, a horizontal generally rectangular frame, supports 60 holding the ends of the frame above the footing, a form of sheet material suspended from the frame, said form including opposite face sheet portions to define a wall and tension elements extending between the face sheet portions, rows 65 of rods extending between the frame and footing and having parts of the face sheet portions secured thereto, the frame and footing having portions providing openings in which the rods are slidably received.

70 4. Form assembly to be employed in the erection of a concrete wall or the like comprising

opposite face portions of flexible sheet material, webs of sheet material connecting the face sheet portions and defining therewith a series of cells, and metal rods secured to each of the face sheet portions adjoining the ends of the webs. 5

5. A form assembly to be employed in the erection of a concrete wall comprising a series of interconnected units of flexible sheet material, each unit of the series including a web portion with loops formed at its ends and with integral 10 face sheet portions extending from the loops and secured to the loops at the ends of the web portion of an adjoining unit.

6. A form assembly to be employed in the erection of a concrete wall comprising a series of 15 interconnected units of flexible sheet material, each unit of the series including a web portion with loops formed at its ends and with integral face sheet portions extending from the loops and secured to the loops at the ends of the web portion 20 of an adjoining unit, and metal rods disposed in each of the loops and having end portions projecting beyond the ends of the loops.

7. A form for pouring concrete comprising a skeletonized framework including sill strips, girt 25 strips, and connecting uprights therebetween, a form assembly of flexible sheet material suspended from the girt strips and defining opposite faces of a wall to be poured, webs of foraminous sheet material connecting the face sheets, and 30 rods having their ends slidably connected to the sill strips and girt strips and having their intermediate portions secured to the face sheet portions of the form assembly, whereby after pouring the rods may be removed from the frame by 35 a vertical sliding movement.

8. A form for pouring with concrete comprising a girt frame assembly, supporting means for the assembly, and cellular units of flexible sheet material suspended from said assembly, said as 40 sembly including units defining a hollow square, and opposite rail sections secured to the square units by clamping bolts, the rails being secured in adjustable overlapping engagement by bolt connections. 45

9. Concrete form comprising a frame including an upper horizontal support, opposite rows of spaced, vertical positioning rods secured to the support, sections of flexible sheet material extending between and secured to said rods, said 50 sheet material being capable of bulging outwardly between the rods under the pressure of concrete poured between the sections, and tension sheets extending between the rods of opposite rows to oppose the pressure of the poured concrete, said sections and sheets defining cellular units into which the concrete may be poured. 55

10. Concrete form comprising spaced, generally vertical positioning elements, sections of flexible sheet material extending between said 60 elements and being capable of bulging outwardly between said elements under the pressure of poured concrete, said sections and elements affording opposite face sheet assemblies, tension elements interconnecting the face sheet assemblies, and a frame-work providing an upper horizontal support to which the assemblies are connected, said support providing openings through which concrete may be poured into the space 65 between the face sheet assemblies.

ALBERT F. BEMIS.
